Fig. 2

Fig. 3

Fig. 5

Fig. 6

Fig. 4

FIGURE 1 is a front elevational view of a hypodermic needle injector in triggered position showing my new design;

FIGURE 2 is a side elevational view of the injector as shown in FIGURE 1;

FIGURE 3 is a top plan view of the injector;

FIGURE 4 is a bottom plan view thereof;

FIGURE 5 is a front elevational view of the injector shown in cocked position; and

FIGURE 6 is a side elevational view of the injector as shown in FIGURE 5.

The rear and side views of the injector not shown in the drawing are respectively the same as those shown in FIGURES 1 and 2.

I claim:

The ornamental design for a hypodermic needle injector, as shown and described.
